UNITED STATES PATENT OFFICE.

GUSTAF WESLEY, OF ST. PAUL, MINNESOTA.

SIGN-FLASHING APPARATUS.

No. 892,477.

Specification of Letters Patent.

Patented July 7, 1908.

Application filed March 7, 1905. Serial No. 248,893.

To all whom it may concern:

Be it known that I, GUSTAF WESLEY, a citizen of the United States, residing at St. Paul, in the county of Ramsey and State of Minnesota, have invented certain new and useful Improvements in Sign-Flashing Apparatus, of which the following is a specification.

My invention relates to improvements in electric sign flashing apparatus, its object being to provide improved means for automatically controlling and lighting lamps or groups of lamps, and consists particularly in providing improved positively operated means for breaking and making the electric circuits.

To this end my invention consists in the features of construction and combination herein-after particularly described and claimed.

20 In the accompanying drawings forming part of this specification, Figure 1 is a top view of the invention showing the face of the dial; Fig. 2 is a side elevation partly in section; Fig. 3 is a top view of a modified arrangement; Fig. 4 shows a modified construction of switch, and Fig. 5 is a detail of a co-operating cam.

In the drawings A represents suitable frame-work upon which is supported a slab 30 or table B. Radially arranged upon the table are knife switches. The blade of each switch has pivotal support 3 upon one end of the insulating base 4, the leaf member 5 of the switch being supported upon the opposite end of the base. Each of the switch-blades is formed of two parallel bars, the upper bar 6 being pivotally connected with the lower main bar 2 by a band 7, said bars being further connected by a spring 8. The outer 40 end of each switch-blade carries a roller 9. By having the switch-blade made up of two connected parallel bars as shown, the upper bar will first leave the leaf member causing slight separation of the bars and resulting in the lower bar being quickly drawn from the leaf-member, preventing arcing. The bases of the switches are secured upon the table by means of the clamping-rings 10 and 11 overlapping the outer and inner edges respectively of the bases and secured to the table by bolts 12 passing through openings in said clamping-plates and table. It thus becomes comparatively easy to change the positions of the switch-bases and to increase or decrease 50 their numbers.

Surrounding the table is a ring 13 supported by arms 14 secured upon the vertical shaft 15. The shaft 15 is journaled in the framework and carries a worm-gear 16 operatively connected with the pulley 17 actuated from a suitable source of power. Carried by posts or arms 18 secured to the ring are two cams 19 and 20, the forward cam 19 having a downwardly projecting end in position to engage the underside of the rollers 9 upon the knife switches, and thereby to force the switch-blades into contact with the respective leaves to close the circuit through the switch so actuated. The rear cam 20 stands above the cam 19 and has a downwardly projecting rear end in position to engage and act upon the upper sides of the rollers 9 of the closed switches to force them down and open the switches.

Below the table B is shown supported a similar table C carrying a ring, cams and switches corresponding in construction and arrangement to the ring, cams and switches arranged in connection with the table B.

In the drawings but one switch is shown supported upon the table C. The table C and its connected parts are adapted to operate in connection with the table A to control the lines of a duplicate sign or of the opposite side of a sign controlled by the table A.

In Fig. 1 is shown diagrammatically the wiring of the switches. From this it will be seen that the leaf-members of the switches are all connected with one of the main lines 21, the blade-members being connected each with one of the lamp groups 22, the lamp group being also connected with the other main line 23. The cams may be adjusted to any position on the ring which may be desired, and by varying the distance between the cams or between the switches, and by varying the number of cams and switches, a great many different combinations of light and colors and method of flashing them may be made.

In Fig. 3 is illustrated a modified arrangement of my invention, in which two separate sets of lamps D and E are employed. The lamps D are connected with the blade-members of the switches upon one side of the switch-board. The lamps E are similarly connected to the blade-members of the switches upon the opposite side of the switch-board. Between these two sets of switches upon opposite sides of the switch-board are

arranged two switches one of which is connected with the leaf-members which control the lamps D, its blade-member being connected with the main line 24. The opposite switch has its blade-member connected with the main line 24 and its leaf-member connected with the leaf-members of the switches which control the series of lamps E. The operating parts of this construction correspond to the operating parts of the preferred construction. In the rotation of the ring the forward cam 19, engaging with the switch connecting the switches of the group D with the main line 24, will close said switch and thereafter engaging with the switches of the group D will successively close said switches and light the lamps in said group. At the same time the opening cam will open the switch which is arranged between the switches of the group E and the main line 24 opening said switch to throw out the lights of the group E and thereafter opening the switches of the group E. The lines of the different groups are thus all turned off at once but are successively turned on.

In Figs. 4 and 5 is shown a modified construction of switch and actuating cam. The actuating cam shown in Fig. 5 is formed with two cam surfaces 25 and 26 which take the place of the cams 19 and 20, and which pass between rollers 27 and 28 carried by the switch.

In the switches shown the roller end of the switch-blade overbalances the opposite end so that the switch when open will remain in open position until closed by the cam.

It will be evident that various modifications in the arrangement of lamps and switches and details of the invention may be made without departing from the invention the scope of which is defined in the claims.

Having now described my invention, what I claim as new, and desire to secure by Letters Patent, is:—

1. In combination, a plurality of radially arranged knife-switches, a plurality of cams, and means for carrying one cam into position successively to engage with and open said switches and the succeeding cam into

position successively to engage with and close said switches.

2. In combination a plurality of knife switches, a surrounding rotary ring, cams carried by said ring in position to successively engage with and close said switches, and means for rotating said ring.

3. In combination a plurality of radially supported knife switches, a surrounding rotary ring, a cam carried by said ring in position to engage with and depress the switch-blade, a cam carried by said ring in position to engage with and raise the switch-blade, and means for rotating said ring.

4. In combination a plurality of radially supported knife switches, the blade of each switch consisting of a pair of spring connected parallel bars, a rotary ring surrounding said switches, a cam carried by said ring in position to engage with said blade to turn the same to open position, a cam carried by said ring in position to engage each of said switches to carry the same to closed position, and means for rotating said ring.

5. In combination a support, a plurality of knife switches radially arranged thereon, means for adjustably holding said switches in position consisting of clamping-rings connecting the opposite ends of said switches with the support, means for actuating said switches consisting of a rotary ring, actuating cams carried by said ring, and means for rotating said ring.

6. In combination a support, a group of switches, means for adjustably supporting said switches in radial position upon said support, means for opening and closing said switches consisting of a rotary ring surrounding said support, opening and closing cams carried by said ring in position to engage with said switches, and means for rotating said ring.

In testimony whereof I affix my signature in presence of two witnesses.

GUSTAF WESLEY.
